Primary Examiner — Khawaja Anwar*Assistant Examiner* — Julice Seung Eun Oum(74) *Attorney, Agent, or Firm* — Quickpatents, LLC; Kevin Prince(57) **CLAIM**

The ornamental design for a modular weight adapter, as shown and described.

DESCRIPTION

FIG. 1 is a top perspective view of a modular weight adapter, showing my new design;

FIG. 2 is an exploded top perspective view thereof;

FIG. 3 is a front elevational view thereof;

FIG. 4 is a right-side elevational view thereof, the left-side elevational view being a mirror image thereof;

FIG. 5 is a rear elevational view thereof;

FIG. 6 is a top plan view thereof;

FIG. 7 is a bottom plan view thereof; and,

FIG. 8 is a bottom perspective view thereof.

The broken lines showing weights and a chain in FIG. 1 depict environmental matter and form no part of the claimed design. The remaining broken lines represent portions of the modular weight adapter that form no part of the claimed design.

1 Claim, 5 Drawing Sheets(56)
